UNITED STATES PATENT OFFICE.

ARTHUR L. BUTLER, OF SOMERVILLE, MASSACHUSETTS.

RAIL SUPPORT.

Application filed December 8, 1925. Serial No. 74,006.

This invention relates to a rail support and particularly to an insulating rail support adapted for use in supporting the third or live rail commonly used in electric rail-
5 way systems.

The object of the invention is to provide a novel and improved construction of rail support and particularly an insulating rail support, which may be constructed of uni-
10 form height and at a minimum cost, which can be assembled in a minimum time, and in which the parts are firmly secured together.

To these ends, the rail support is provided 15 with a cap member and a base member, each provided with a socket having a bottom wall, and an intermediate member, preferably of insulating material which is interposed between said cap and base members and has 20 its ends extended into said sockets to engage the bottom walls thereof and thereby uniformly space the cap member from the base member.

The sockets in the cap and base members 25 are preferably cylindrical in shape, and the walls of said sockets are provided with stationary and movable sections between which the ends of the intermediate member are firmly clamped as will be described.

30 These and other features of the invention will be hereinafter described and particularly defined in the claims at the end of this specification.

In the drawings illustrating the preferred form of the invention, Figure 1 is a 35 plan view of an insulating rail support embodying the present invention; Fig. 2 is a side elevation of the rail support shown in Fig. 1; Fig. 3 is an elevation with a portion in section of the insulating rail support 40 shown in Fig. 1 looking toward the left; Fig. 4 is a section taken on the line 4—4 of Fig. 3; and Fig. 5 is a detail in perspective of one of the clamping members to be 45 referred to.

Referring to the drawings, the illustrated construction of rail support comprises a cap member 10 and a base member 12, both being preferably cast of metal. The cap mem- 50 ber 10 has provision as will be described, for supporting the rail thereon, and the base 12 is adapted to be bolted to the usual foun- dation or support.

The cap and base members 10, 12 are pro- 55 vided with sockets 14, 15 having bottom or end walls 16, 17, which are engaged by the

ends of an intermediate member 18 which is interposed between the cap and base mem- 60 bers 10, 12, and which serves to maintain the cap member 10 at a predetermined eleva-
tion above the base member 12.

Provision is made for detachably clamp- 65 ing the ends of the intermediate member 18 within the sockets 14, 15, and for this pur- pose as herein shown, the side wall of each 70 socket is provided with a stationary section 19 and with a movable section 20 which co- 75 operate to form practically a continuous wall for said socket. The movable section 20 of the socket wall is preferably made as a block 70 of substantial thickness which slides in an opening or slot 21 between the ends of the stationary section of the side wall, and which co-operates with the end of the intermediate member 18 to clamp it against the stationary 75 section 19.

Each clamping member 20 is provided with a hole 22 through which a clamping bolt 24 may be extended to pass through a 80 preformed hole in the end of the interme- 85 diate member 18 and through a hole in a boss 26 extended from the stationary member 19 of the socket side wall and located dia- metrically opposite the hole in the clamping member or section 20 when the latter occu- 85 pies its operative clamping position, as shown in Figs. 3 and 4.

In the present instance, the clamping member 20 is provided with lugs 28 between 90 which the head 29 of the clamping bolt is received, and the lugs 28 serve to prevent ro- 95 tation of the bolt when the clamping nut 30 upon the threaded end of the bolt is screwed up against the end of the boss 26 in the op- 95 eration of clamping the member 20 against the end of the intermediate member 18.

In practice it is preferred to employ a 100 standard construction of clamping bolt and nut commercially known as the O K bolt, which is capable of compensating for shrink- 105 age in the intermediate member 18 (when the latter is of wood), to the end that the clamping member 20 may be maintained in firm engagement with the intermediate member 18.

When the invention is embodied in an in- 110 sulating rail support adapted for use in supporting third or live rails, the interme- diate member 18 comprises preferably a cy- lindrical pin of wood which is dipped in paraffin to render it weather-resistant.

The cylindrical form of the insulating

member enables the latter to be made at a minimum cost. It is also preferred to provide the insulating member with metal bushings 35 for the clamping bolts 24.

5 Provision is made for securing the rail to be supported in operative position upon the cap member 10, and for this purpose as herein shown the cap member 10 is provided with a pair of rail-engaging members comprising preferably hooks 40, 41. The hook 40 is formed integrally with the cap member 10 and is adapted to hook over one flange of the base of the rail. The hook 41 is removably secured to the cap member, and as herein shown is provided with a shank 44 extended between the arms of a yoke 45 upon the cap member and held in a rail-engaging position by a heavy cotter pin 46 extending through holes of the arms of the yoke and through a hole in the shank 44 of the hook 41, as illustrated in Figs. 1 and 2.

The cap member 10 is also provided with a petticoat or shield 47 for shedding rainwater away from the intermediate member 18.

25 From the description thus far it will be observed that the present construction of rail support is simple and may be manufactured at minimum cost. The cylindrical sockets 14, 15 permit the use of the simplest and most inexpensive form of insulating pin or member 18, thereby reducing the cost of manufacture of the rail support in this respect. The intermediate or insulating members 18 may be made of uniform length and

30 co-operate with the bottom walls of the sockets in the cap and base members 10, 12 respectively, so that when the rail supports are assembled the caps 10 thereof are all located at a uniform height above the foundation upon which the rail supports are mounted.

It will also be observed that the clamping bolt 24 extending through the insulating member 18 affords a rigid and durable connection between the insulating member and the cap and base, thus insuring a rigid and unitary construction of rail support. The manner in which the ends of the intermediate or insulating member 18 are secured within the sockets 14, 15 enables a stock fastening device in the form of an O K bolt for automatically taking up the shrinkage in the wooden insulating member to be used. This not only serves to maintain the insulating member tightly clamped in the sockets, but also enables this to be done at minimum manufacturing expense.

While the preferred embodiment of the invention has been illustrated and described, it will be understood that the invention may 60 be embodied in other forms within the scope of the following claims.

Having thus described the invention, what is claimed is:—

65 1. In a rail support, in combination, a cap member and a base member, each provided

with a socket having a bottom wall and a side wall provided with a stationary and a movable section, an intermediate member interposed between said cap and base members and having its opposite ends inserted into 70 said sockets and co-operating with the bottom walls thereof, and bolts extended through said intermediate member and co-operating with the movable sections of said socket walls to clamp the ends of said intermediate member against the stationary sections of said socket walls.

2. In a rail support, in combination, a cap member and a base member, each provided with a cylindrical socket having a bottom 80 wall and a side wall, the latter having a stationary and a movable section, an intermediate member having cylindrical ends inserted into said sockets, and co-operating with the bottom walls thereof, and bolts extended through said intermediate member and co-operating with the movable sections of said socket walls to clamp the ends of said intermediate member against the stationary sections of said socket walls.

3. In a rail support, in combination, a cap member and a base member, each provided with a socket having a bottom wall and a side wall provided with a stationary and a movable section, an intermediate member interposed between said cap and base members and having its opposite ends inserted into 90 said sockets and co-operating with the bottom walls thereof, metal bushings in said intermediate member, and bolts extended through said bushings and intermediate member and co-operating with the movable sections of said socket walls to clamp the ends of said intermediate member against the stationary sections of said socket walls.

4. In a rail support, in combination, a cap member and a base member, one of said members having a socket provided with a bottom wall, an intermediate member interposed between said cap and base members and extended into said socket, a movable clamping member co-operating with the side of said intermediate member, and a bolt co-operating with said clamping member and extended through said intermediate member.

5. In a rail support, in combination, a cap member and a base member, each provided with a cylindrical socket having a bottom wall and a side wall, the latter having a stationary section and a movable section, an intermediate cylindrical insulating member having its ends extended into said sockets and provided with transverse openings, and bolts extended through said transverse openings and co-operating with the movable and stationary sections of said socket walls to clamp the insulating member between them.

In testimony whereof, I have signed my name to this specification.

ARTHUR L. BUTLER.
